[57] CLAIM

The ornamental design for a chef's accessory belt, as shown and described.

DESCRIPTION

FIG. 1 is a perspective view of a chef's accessory belt showing my new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a perspective view thereof, with the dashed lines showing the outline of typical accessories and a person wearing the chef's accessory belt for illustrative purposes only and forming no part of the claimed design.

The rear side of the accessory belt is not ornamented.
